Merchant and Taylor

UNITED STATES PATENT OFFICE

GEORGE L. CURLE, OF MINNEAPOLIS, MINNESOTA

RACK FOR MATRIX MAGAZINES

Application filed November 15, 1928. Serial No. 319,565.

My present invention has for its object the provision of a simple and highly efficient rack for matrix magazines and to such ends, it consists of the novel devices and combinations of devices hereinafter described and defined in the claims.

Various different, more or less crude and cumbersome devices or methods are now used for holding matrix magazines, containing sets or fonts of circulating matrices with characters of different sizes and styles, where any one thereof may be transferred when wanted to a type casting machine. These devices support the matrix magazines out in the open and in upright positions where more or less dust and dirt accumulates on the matrices contained therein through the open tops of said magazines which of course, is detrimental thereto. Furthermore, these devices or methods are such as to make it very awkward and difficult to handle matrix magazines during their application to a type setting machine or in the removal therefrom. Said devices also take up a great deal of valuable space.

In applying a matrix magazine to a type casting machine or in removing the same therefrom the natural and most convenient way of handling the same is to grasp the matrix magazine at its edge portions and hold the same in an upright position and in which position the spilling of some of the matrices therefrom is eliminated.

The aims of this invention are to facilitate the handling of matrix magazines, to store or hold the same in a compact space where they are protected from dust and dirt and to provide a closure for the open top of a matrix magazine to prevent the spilling of the matrices therefrom during the placing of a matrix magazine in the rack, or the removal of the same therefrom. A further aim of the invention is to provide suitable identifying means for the different matrix magazines in the rack, each of which contains a set or font of matrices with characters of a given size and style, whereby a matrix magazine containing the desired set or font of matrices to be used may be readily selected and removed from the rack with-

out disturbing or handling the other magazines in the rack.

The improved rack is adapted to receive a matrix magazine in the same position, to wit: an upright position, in which it is carried from a type setting machine and sustain the same with freedom for vertical swinging movement whereby, the lower end thereof may be lifted to bring the matrix magazine into a horizontally inclined position when it may be moved upper end first into the rack. At the limit of this movement of a matrix magazine into the rack the same is held against movement out of the rack and in a position to permit another matrix magazine to be sustained in an upright position in front thereof.

To remove a matrix magazine from the rack it is first released from its holding means and drawn outward of the rack and its outer end lowered to bring said magazine into an upright position. With the matrix magazine being removed from the rack thus sustained it may be grasped at its vertical edge portions and lifted from the rack in an upright position and carried to a type casting machine and placed therein. The edge portions of a matrix magazine are in upwardly diverging relation so that there is plenty of clearance for a person's hands holding the same between the sides of the rack and matrix magazine when placing said magazine in the rack or removing the same therefrom.

In the accompanying drawings, which illustrate the invention, like characters indicate like parts throughout the several views.

Referring to the drawings:

Fig. 1 is a fragmentary perspective view of the improved rack;

Fig. 2 is a perspective view of one of the closures for a matrix magazine removed from the rack;

Fig. 3 is a perspective view of one of the identifying plates removed from the matrix magazine;

Fig. 4 is a fragmentary view of the upper portion of the rack with some parts shown in central vertical section;

Fig. 5 is a fragmentary detail view showing one of the matrix magazines sustained in an upright position at the front of the rack with its closure shown in transverse vertical section; and

5 Fig. 6 is a perspective view of one of the matrix magazines.

In the drawings, there is illustrated a plurality of matrix magazines 7, each of which has on its under side three transverse stiffening bars 8 and an entrance rail 9 which extends longitudinally of said magazine and is rigidly secured to the outer faces of the bars 8. The upper most bar 8 has its end portions extended outward of the edges of the matrix magazine 7 to afford a pair of arms 10. It will be noted that the edges of the matrix magazines 7 are in upwardly diverging relation. Each matrix magazine 7 contains a set of font of circulating matrices 11.

20 The improved rack, as shown, includes a rectangular upright sheet metal casing 12 closed except at its front. Angle track rails 13 are secured to the inner sides of the casing 12, arranged in vertically spaced pairs and are inwardly and upwardly inclined. These track rails 13 have at their outer ends upstanding stop lugs 14. A long roller 15, which extends the full width of the casing 12, is provided for each pair of track rails 13. These rollers 15 are loosely mounted on long rods 16 the ends of which are rigidly secured to the anchoring flanges of the track rails 13 and the sides of the casing 12. The upper 35 faces of the rollers 15 are positioned slightly below the pairs of track rails 13 and inward of the outer ends thereof, see Fig. 4.

40 Mounted in the casing 12 below the track rails 13 is a chest of drawers 17. Slidably mounted on each pair of track rails 13 is a closure 18 for the open top of the matrix magazines 7 mounted thereon. This closure 18 is in the form of a flat plate which projects perpendicular to the track rails 13 and is integrally formed with the upper edge of a carrier 19 in the form of a flat body plate which slidably rests on said rails. Integral- 45 ly formed with the carrier 19 at the ends of its lower edge and overlying the track rails 50 13 is a pair of upstanding retaining lugs 20.

The outward sliding movements of the carriers 19 on the track rails 13 are limited by the engagement of the retaining lugs 20 with the stop lugs 14 and the inward sliding move- 55 ments of said carrier are limited by the engagement of the closure 19 with the back of the casing 12. The lateral spacing of the track rails 13 of the several pairs is such as to freely receive the upper or widest portions of the matrix magazines 7 therebetween and with their arms 10 mounted on the body plates 19 for compound pivotal and sliding move- 60 ments.

65 The sliding movements of the arms 10 on the carriers 19 are limited by the closures 18

and retaining lugs 20. By reference to Figure 2, it will be noted that the carriers 19 are recessed at 21 the full distance between the retaining lugs 20 to afford clearance for the matrix magazines 7 and permit the same to be sustained in upright positions, one of which is shown in Figure 5. Said carriers 19 are further recessed or notched at 22 to afford clearance for the entrance rails 9 when the matrix magazines 7 are turned into a 75 horizontally inclined position. When the rack is empty of matrix magazines 7 the carriers 19 are gravity held at the lower or outer ends of the track rails 13 with the retaining lugs 20 engaging the stop lugs 14.

To remove a matrix magazine from a type casting machine and store the same in the improved rack said magazine is held at its upwardly diverging edge portions in an upright position and carried in this position to the rack where the under side of the matrix magazine is turned toward the open front of the casing and with its arms 10 positioned on one of the carriers 19 and against its retaining lugs 20 for sustaining the matrix magazine 7 in an upright position in front of the other matrix magazine 7 in the rack. The lower end of this upright matrix magazine 7 is then raised by swinging said magazine vertically outward to bring the same into substantially the plane of the respective pair of rails 13 and at which time the arms 10 turn on the carrier 19 to permit the movement. While this matrix magazine 7 is thus held it is pushed into the rack between the respective pair of rails 13. During the initial movement of the matrix magazine 7 into the rack its arm 10 slides on the carrier 19 and thereby brings the open top of said magazine into contact with the closure 18 and closes the same to prevent the spilling of any of the matrices therefrom.

100 Further movement of the matrix magazine into the rack will cause the carriers 19, by the engagement of said magazines with the closure 18, to slide on the track rails 13 and move with said magazine. During the movement of the matrix magazine into the rack its entrance rail 9 rests on the underlying roller 15 and together with the arms 10 supports 105 said magazine in the rack.

110 The engagement of the closure 18 with the back of the casing 12 limits the movement of the matrix magazine 7 into the rack and at which time its entrance rail 9 passes beyond the engaged roller 15 and drops back of the same and affords a stop to prevent the matrix magazine from sliding out of the rack. After the entrance rail 9 passes out of engagement with the roller 15 the under plate 115 of the matrix magazine 7 drops onto said roller and supports the lower or outer end portion of said magazine therefrom.

120 It will be noted that when a matrix magazine 7 is held in the rack by the engagement 130

of its entrance rail 9 with the roller 15 the outer or lower end of said magazine is spaced from the stop lugs 14 a distance sufficient to permit another matrix magazine to be sustained in an upright position in front thereof by having its arms 10 mounted on one of the carriers 19.

To remove a matrix magazine from the rack the outer or lower end thereof is raised sufficiently to disengage its entrance rail 9 from the roller 15 and a slight outward pull on said magazine will cause the carrier 19 to slide downward on the track rail 13 and at which time said entrance rail 9 will travel on the roller 15. The engagement of the retaining lugs 20 with the stop lugs 14 limit the outward movement of the carrier 19 and thereafter the arms 10 will have a limited sliding movement on the carrier 19 until stopped by the lugs 14. The outer end of the matrix magazines 7 is turned down to bring said magazines into an upright position where it is sustained by its arms 10 from the carrier 19 and retaining lugs 20.

With the matrix magazine thus sustained the same may be grasped at its upwardly diverging edge portions and lifted from the rack in an upright position and carried to a type casting machine.

The track rails 13 and carrier 19 may be kept greased so that said carriers will freely slide on said track rails. By sustaining the matrix magazines 7 in the rack in substantially horizontal positions and with their open tops at the closed back of the casing 12, said magazines are protected from dust and dirt.

A plate 23 having identifying characters is attached to the lower end portion of each matrix magazine near the lower end thereof. The characters on these plates 23 may be easily read through the open front of the casing 12 in view of the position of the plates 23 on the matrix magazines and the inclination at which said magazines are held in the rack. Each matrix magazine 7 is provided with an identifying numeral on its plate 23 and the other characters thereon identify the size and style of the characters on the matrices carried in said magazine.

One of the drawers in the chest 17 is assigned to each matrix magazine 7 and given the same identifying numeral which appears on a plate 24 attached to said drawer. The purpose of the chest of drawers 17 is to hold extra matrices for the several matrix magazines.

What I claim is:

1. A rack for a matrix magazine having at its upper end a pair of arms which project outward of the edges thereof, said rack having a pair of track rails spaced to receive a matrix magazine therebetween with its arms removably mounted on the track rails to sustain the magazine for compound pivotal and

sliding movements into and out of the rack, and a sustaining member in the rack for holding the lower end of the magazine raised.

2. The structure defined in claim 1 in further combination with stops at the outer ends 70 of the track rails to limit the outward movement of the arms on the track rails.

3. The structure defined in claim 1 in which the sustaining member is arranged to be engaged by a part on the magazine to hold said magazine against outward movement from 75 the rack.

4. A rack for a matrix magazine having at its upper end a pair of arms which project outward of the edges thereof, said rack having a pair of upwardly and rearwardly inclined track rails spaced to receive a matrix magazine therebetween with its arms removably mounted on the track rails to sustain the matrix magazine for compound pivotal and 80 sliding movements into and out of the rack, said track rails having stops at their outer ends for the arms to limit the sliding movement of the magazine out of the rack, and a roller on which the magazine slides during its movement into and out of the rack and for sustaining the lower end of the magazine when in the rack.

5. A rack for a matrix magazine having at 90 its upper end a pair of arms which project outward of the edges thereof and also having a longitudinally extended entrance rail, said rack having a pair of upwardly and rearwardly inclined track rails spaced to receive a matrix magazine therebetween with its arms 95 removably mounted on the track rails to sustain the magazine for compound pivotal and sliding movements, said track rails having stops at their outer ends for the arms to limit the sliding movement of the magazine out of the rack, and a roller on which the entrance rail travels during the sliding movement of the magazine into or out of the rack and for holding the lower end of the magazine raised when in the rack.

6. The structure defined in claim 5 in which the roller is arranged to be engaged by the lower end of the entrance rail when the magazine is in the rack to hold said magazine against outward sliding movement from the rack.

7. A rack for a matrix magazine having at its upper end a pair of arms which project outward of the edges thereof, said rack having a plurality of vertically spaced pairs of track rails spaced to receive a matrix magazine therebetween with its arms removably mounted on the track rails of one of said pairs, said track rails having stops at their outer ends to limit the sliding movement of the matrix magazine out of the rack, and sustaining means for holding the outer ends of the magazine raised when in the rack and against outward sliding movement from the rack, said sustaining means being arranged to 110

hold the magazine spaced from the stops at the outer ends of the rails to permit another magazine to be sustained by its arms in an upright position in front of a magazine in the rack.

8. A rack for a matrix magazine having at its upper end a pair of arms which project outward of the edges thereof, said rack having a plurality of vertically spaced pairs of track rails, the rails of said pairs being spaced to receive a matrix magazine therebetween with its arms removably mounted on one pair of said track rails, said track rails having stops at their outer ends to limit the sliding movement of magazines out of the rack, a roller for each pair of track rails on which a magazine slides during its movement into or out of the rack and for sustaining the lower end of said magazine when in the rack, said magazines having parts arranged to engage the rollers to hold the magazine against outward sliding movement from the rack and spaced from the stops at the outer ends of the track rails to permit a magazine to be sustained by its arms in an upright position in front of a magazine in the rack.

9. A rack of the class described having means for sustaining an open top matrix magazine for compound pivotal and sliding movements in which it may be retained either in an upright position at the front of the rack or in an inclined position within the rack, and a closure arranged to close the open top of the magazine when moved into said inclined position.

10. A rack of the class described having means for sustaining an open top matrix magazine for compound pivotal and sliding movements in which it may be retained either in an upright position at the front of the rack or in an inclined position within the rack, and a closure for the open top of the magazine arranged to partake of the sliding movement of the magazine, said closure being arranged to close the open top of the matrix magazine when moved from an upright position to said inclined position.

11. The structure defined in claim 10 in further combination with stops arranged to limit the outward sliding movement of the closure in the rack, said closure having a limited sliding movement in respect to the magazine whereby the open top of the magazine may be closely positioned to the closures when moved into the rack and moved away from the closure when the magazine is moved out of the rack.

12. A rack for an open top matrix magazine having at its upper end a pair of arms which project outward of the edges thereof, said rack having a pair of track rails a closure for the open top of the magazine slidably mounted on the track rails, the arms of the magazine being removably and pivotally mounted on the closure for sustaining

the magazine in an upright position at the front rack or for sliding movement therewith in a horizontally disposed position within the rack, said closure being arranged to close the open top of the magazine when in said horizontal position.

13. The structure defined in claim 12 in further combination with stops for limiting the sliding movement of the closure on the track rails, and in which the arms of the magazine have a limited sliding movement on the closure, whereby when the closure has reached its inner most position in the rack the magazine may be moved in respect thereto to closely position its open top to the closure and be moved away from said closure during its sliding movement out of the rack.

14. A rack for individually supporting a plurality of matrix magazines vertically spaced the one above the other in upwardly and rearwardly inclined positions, said magazines having symbols on their upper faces at the lower end portions thereof that are readable between the vertically spaced magazines in the rack.

15. A rack having a plurality of vertically spaced pairs of upwardly and rearwardly inclined track rails for individually supporting matrix magazines vertically spaced the one above the other in rearwardly and upwardly inclined positions, said magazines having symbols on their upper faces at the lower end portions thereof that are readable between the vertically spaced magazines in the rack.

In testimony whereof I affix my signature. 100
GEORGE L. CURLE.
